INDUCTION HEATING

Nelson B. Stevens, Woodhaven, N. Y., assignor to
 Induction Heating Corp., New York, N. Y., a
 corporation of New York

Application June 18, 1943, Serial No. 491,304

2 Claims. (Cl. 219—13)

This invention relates to induction heating, and apparatus therefor, which is particularly adapted among other possible uses, for internally heating objects with small cavities.

The internal induction heating of objects such as engine cylinders and the like has generally heretofore been accomplished by inserting a work coil having a number of turns arranged coaxially with the cylinder or cavity. But such an arrangement would be difficult and have serious disadvantages if applied to the problem of internally heating cavities of small diameter. The conductor turns of the work coil have to be relatively large in order to embody a cooling fluid conduit and also to be able to conduct sufficient power for rapid heating effects. Hence, if the cavity to be heated is small, there will be insufficient space available for convenient coaxial arrangement of the conductor turns, and in general it would be difficult to conduct sufficient high frequency power into the cavity for rapid, economical heating.

According to the present invention, the above noted difficulties are avoided by using a work "coil" comprising preferably a single turn having the general shape of a hairpin, adapted to be inserted longitudinally into the small cavities to be heated. Such a hairpin turn, when its terminals are connected to a source of high frequency power, sets up a magnetic field, the lines of force of which mostly extend in planes perpendicular to the longitudinal center line of the turn, as contrasted with the prior practice where the lines of force extend along planes which are parallel to, or include the axis of the turn. The hairpin-like turn may be arranged with its center line coinciding with or extending along the axis of the cavity, and in order to insure uniform application of the field around the walls of the cavity, the object being heated is preferably rotated about the cavity axis.

Various further and more specific objects, features and advantages of the invention will more clearly appear from the detailed description given below taken in connection with the accompanying drawings which form a part of this specification and illustrate merely by way of example, preferred forms of the invention. The invention consists in such novel features, arrangements and combinations of parts, and methods as may be shown and described in connection with the apparatus herein disclosed.

In the drawings:

Fig. 1 is a side elevational view of a preferred 55 as at 21. Also these conductor bars may be

form of apparatus assembly embodying the invention;

Fig. 2 is a sectional view taken substantially along line 2—2 of Fig. 1;

5 Fig. 3 is a sectional view taken substantially along lines 3—3 of Fig. 2;

Fig. 4 is a top view of the means for connecting the work coil to the high frequency source of power;

10 Fig. 5 is a sectional view along lines 5—5 of Fig. 4;

Fig. 6 is a view similar to Fig. 2 but showing an alternative embodiment of the invention; and

15 Figs. 7, 8 and 9 illustrate a further example of the invention.

In Fig. 1 portions of a high frequency source of power are shown in the form of a transformer 10 having a secondary 11 and forming a part of high frequency generator equipment such for example as shown in patent to Dravneek No. 2,321,189. Secondary terminals for the transformer are shown at 12, 12'. These respectively may be connected to lugs as at 13, 13', on which a pair of conductor bars 14, 14' are supported, as shown in further detail in Fig. 4. A cooling fluid conduit as at 15 of non-magnetic metal may be brazed to one of the lugs 13 and also along the bar 14 as at 15'. The outer end of bar 14 may be bent downwardly as at 16, and formed as 25 shown in Fig. 2 with a somewhat angularly disposed drill hole 17, through which the conduit 15' extends. From the lower end of portion 16, the conduit 15' is continued in the form of a depending hairpin-shaped work "coil" 18 adapted 30 to be inserted in the cavity 19 of an object 20, which is to be heated internally.

The return end or terminal of the work "coil" 18 may pass up through a drill hole as at 17' within a depending portion 16' on the conductor bar 14', and thence back to the transformer to a fluid outlet, in a symmetrical arrangement with respect to the corresponding other half of the structure above described. Thus, the cooling fluid conduit 15, 15' may be integrally formed as one single piece of metal tubing, together with the work "coil" 18 and the return connection therefor.

50 The term work "coil" as herein used is intended to apply to substantially that part of the structure, such as at 18, which is to be in active coupling relation with the work piece.

As shown in Figs. 2 and 5, the conductor bars 14, 14' may be separated by a strip of insulation 55 as at 21. Also these conductor bars may be

secured together by two or more insulated bolts as at 22.

As shown, the transformer 18 may be mounted on a platform 23 forming part of a cabinet structure having a front panel 24 formed with an aperture 25, through which the work coil supporting structure extends. A housing 26 may be located in front of the panel 24 for containing apparatus for elevating and lowering the work piece 20 into and out of operating position, and for also rotating the same during the treatment. This apparatus may for example comprise a platform 27 slideable vertically on ways at 28, within the housing 26, so as to elevate or lower the upper part of the housing 26 and the mechanism contained therein. The means for raising or lowering the platform 27 may for example comprise a hydraulic piston arrangement of suitable known form as at 30.

A motor 31 may be mounted on the platform 27 and connected by gearing as at 32, to rotate a vertical shaft 33 provided at its upper end with suitable coupling means as at 34, for receiving the work pieces 20. The shaft 33 and the coupling 34 are preferably so constructed and arranged as to be coaxial with the principal axis or vertical center line of the cavities in the work pieces. Thus with the form of the invention shown in Figs. 1-3, the vertical center line of the work coil will be the same as the axis of rotation of the work piece.

Before the apparatus of FIG. 1 is placed in operation, the hydraulic piston means 30 is operated to bring the upper part 26 of the housing and the mechanism therein, to their lowermost positions. Thereupon one of the work pieces 20 may be coupled in place and the piston means operated to elevate the work piece and its rotating apparatus, up to a position so that the work coil will be inserted in the cavity 16 to the desired depth, as shown in FIG. 2. The motor 31 is then started for rotating the work piece, and meanwhile the high frequency generator is started so that a high frequency electromagnetic field is maintained about the conductor parts comprising the work coil 18. Due to the relative rotation of the work coil and the work piece, all of the inside surface of the cavity 16 will be uniformly heated at the different points about the axis.

Since the lines of force encircling the two sides or branches of the work coil 18 will be established to extend in planes perpendicular to the cavity axis, the degree of close coupling between the work coil and the metal of the work piece will be considerably improved, thus improving the heating efficiency as compared with what could be obtained if the work coil turn were arranged coaxially with the cavity axis. That is, the lines of force encircling the vertical portions of the work coil 18 will tend to more nearly coincide with the circular cavity, whereby the percentage of each line of force which occurs in an air gap will be smaller and consequently the reluctance of its magnetic circuit will be less.

With the particular example of work coil shown in FIG. 2, the side portions are bowed somewhat inwardly toward the longitudinal center line, whereby the portions toward the lower or head end, and toward the upper or terminal ends, extend gradually outwardly from the center line, as compared with the intermediate portions of the turn. This shape permits closer coupling with the work piece at the upper and lower end portions of the cavity for thereby sup-

plying more heat to these portions. This is desirable for producing a substantially uniform heating effect in the work piece throughout the depth of the cavity. That is, at the upper open end of the cavity there will be a greater loss of heat by radiation, thus requiring the supplying of more heat at this portion if it is to be heated to the same degree as the middle portion. Also since the lower portion of the cavity is surrounded by a larger amount of metal, more heat is required to raise the temperature of this portion to the same degree as that of the middle portion. Hence the bowed side portions, as shown, provide a simple expedient for accomplishing uniform heating of the cavity walls throughout the height thereof. The desired uniform heating at different points about the axis is, as above explained, accomplished by the relative rotation of the coil and work piece. The degree to which the side portions of the turn must be bowed, may be readily determined by trial, and will of course depend upon the shape and proportions of the work piece and its cavity.

As shown in FIGS. 2 and 3, the work piece 20 is intended to have fin portions 38' brazed to its outer surface by the induction heating of the member 20 internally. That is, the fins may be initially held in place by any suitable clamping means (not shown) and with brazing metal strips extending along the base of each fin. Then upon inductively heating the member 20 internally in the above described manner, the brazing metal will melt and creep beneath the base edges of the fins by capillary action. In case only one fin or other object is to be brazed onto the exterior of the work piece, or in case only two objects are to be attached at angularly spaced positions, it may only be necessary to heat the portions of the work piece adjacent the areas where the objects are to be attached. In such cases the work coil and work piece may not need to be relatively rotated during the heating, as ample heat may be applied with the side portions of the work coil in relatively stationary positions, using either the type of work coil shown in FIG. 2 or those hereinafter described in connection with FIGS. 6-8.

With the form of the invention shown in FIG. 6, the work coil turn 38 is also of the general shape of a hairpin, but in this case the sides of the turn, toward the terminal portion are gradually and progressively spread apart somewhat as compared with the lower or head portion. This form is well adapted for internally heating a bullet core mold as at 36, the lower portion of the cavity of which is quite restricted in diameter. The work piece 36 may be mounted on a suitable supporting member as at 38, which in turn is carried by a shaft 39, so arranged as to permit rotation as indicated, and also vertical movement for insertion and removal of the work piece as in the case of FIG. 1. After the work piece 36 has been heated to a sufficient temperature for the desired heat-treating, water or other quenching fluid may be introduced into the cavity as through a nozzle 38' positioned with its tip in between the spread-apart terminals of the hairpin turn 38.

While the examples of FIGS. 2 and 6 both involve internal heating of small diameter surfaces of revolution, it will be understood that the same or similar apparatus may be used in practice for heating within cavities of non-circular cross section. Although in that case the degree of uniformity of heating at different points about the

center line of the cavity will not be quite so exact, yet since the cavities are small, the heat will be generally adequately distributed by conduction in the metal and also to some extent by the effects of eddy currents.

Figs. 7-9 show a suitable form of work coil 40, also of the general shape of a hairpin for heating the walls of a cavity as at 41 having restrictions as at 42, 43 at various elevations. In this case the work piece 44 containing the cavity may be mounted on a vertically movable support 45, rotatable about the vertical axis of the cavity 41. The incoming conductor portion 46 (Figs. 8, 9) extends along and adjacent one element of the surface of revolution of the cavity, then reversing at 47 for extension as at 48 along and adjacent another element of such surface, and thence out of the cavity.

The side portions of the hairpin configuration are both bent in the same directions to laterally offset positions as at 49, 50 (Fig. 7), thereby providing a shape to substantially correspond to the contour of elements of the side walls of the cavity at portions of varying diameters. Because of these laterally offset portions, this form of work coil turn cannot be arranged with its two side portions symmetrical with the axis of the cavity, and with close coupling relationship to the cavity walls, while still permitting insertion and removal of the work coil. Accordingly, here the vertical center line of the work coil is preferably arranged along but in spaced relation to the vertical axis of the cavity, as is best shown in Fig. 9. This still permits both side portions of the hairpin configuration to extend along in close inductive relation with elements of the surface of revolution being heated. To insert or remove the work piece in the apparatus without jamming the offset portions 49, 50 against the walls of the cavity, it is first necessary of course to slide the work piece sideways to bring the work coil to a more central position to clear the restrictions 42, 43.

Hairpin-like coil turns such as of Fig. 7, are also adapted to heat straight-walled cavities to different degrees at different elevations. For that purpose, offset portions as at 49, 50 would be located at elevations where less heating is desired.

With the above described examples of the invention, it has been found possible to quickly heat to redness the internal walls of objects such as shown, upon making flow through the work

coil turn, current at a frequency for example of 375,000 cycles. It is found that such objects having cavities for example of about $\frac{1}{2}$ inch in diameter, and $1\frac{1}{2}$ inches in depth, could be thus heated by supplying to the work coil about 5 kilowatts at such frequency, and with approximately 300 volts across the upper ends of the hairpin turn.

While the invention has been described in detail with respect to a certain preferred example, it will be understood by those skilled in the art after understanding the invention that various changes and modifications may be made without departing from the spirit and scope of the invention, and it is intended therefore in the appended claims to cover all such changes and modifications.

What is claimed as new and desired to be secured by Letters Patent is:

- 20 1. A high frequency work "coil" for applying heat by magnetic induction inside a cavity of an object, comprising a turn formed with a cooling fluid cavity therein and having the general shape of a hairpin, the sides of which are bowed somewhat inwardly toward the longitudinal center line, whereby the portions toward the head end and toward the terminals extend gradually outwardly from said center line as compared with the intermediate portions of the turn.
- 25 2. Method for the induction heating of the internal walls of small diameter cylindrical cavities, which comprises the steps of inserting a hollow conductor turn into the cavity in position to extend along and adjacent one element of the side wall of the cavity, then across and returning along and adjacent another element of the side wall of the cavity and out thereof, the sides of said turn which extend along said elements being so positioned as to be bowed some-
what inwardly toward the longitudinal center line of the cavity, whereby the portions of the turn toward the outlet end of the cavity and to-
ward the base of the cavity extend gradually outwardly from said center line as compared to
the intermediate portions of the turn, conduct-
ing a stream of cooling fluid through the hollow turn, and applying high frequency current to the turn, whereby heating of the cavity walls is caused by a magnetic field having its lines of force extending along planes generally perpen-
dicular to the axis of the cavity.
